DESIGN FOR A CLOTHES HANGER

George F. Dixon, West Point, N. Y.

Application June 7, 1946, Serial No. 130,500

Term of patent 3½ years

(Cl. D80—8)

To all whom it may concern:

Be it known that I, George F. Dixon, a citizen of the United States of America, residing at West Point, in the county of Orange, State of New York, have invented a new, original, and ornamental Design for a Clothes Hanger, of which the following is a specification, reference being had to the accompanying drawing, constituting a part thereof.

Fig. 1 is a front elevational view of a clothes hanger, showing my new design; and

Fig. 2 is a vertical sectional view thereof taken along the line 2—2 of Fig. 1.

The back of said hanger is conventionally plain.
I claim:

The ornamental design for a clothes hanger, substantially as shown and described.

GEORGE F. DIXON.
